THERMALLY RESPONSIVE SWITCH ADAPTED TO FUNCTION AS A HIGH LIMIT SWITCH OR AS A FAN SWITCH WITH A FIXED ADJUSTABLE TEMPERATURE DIFFERENTIAL

Hollis Lee Randolph, Lakewood, Calif., assignor to Robertshaw Controls Company, Richmond, Va., a corporation of Delaware

Filed Jan. 23, 1962, Ser. No. 168,044
13 Claims. (Cl. 208—138)

This invention relates to electrical control switches of the type in which the switch contacts open and close automatically in response to temperature variations.

Devices of this type are primarily utilized to control the operation of a fan motor in hot air heating systems, or an electrically operated valve in response to a high limit temperature setting. For example, when the temperature in a duct or the like reaches a certain preset temperature, the switch contacts close to start a fan into operation, and upon satisfaction of the heating requirement, the contacts open to shut off the fan. Switches of this type may also be employed as high limit controls; the switch responding to excessive temperature to break the circuit and cause an electrically operated fuel control valve to close and shut down the system.

It is an object of this invention to provide a thermally responsive switch which may be utilized as either a fan switch with a fixed temperature differential, a fan switch with an adjustable temperature differential, or as a high limit switch.

A further object is to provide a thermally responsive switch having improved adjustment mechanism for varying the operating range of the switch.

Still another object is to provide a switch having improved snap actuating mechanism.

A further object is to provide a switch which may be selectively biased to return to either an open or closed position upon removal of external forces.

The objects are achieved by the provision of a switch having a fixed contact and a movable contact, the movable contact being supported by a spring device which is arranged to open and close the contacts with a snap action upon the application of an external force. For actuating the contacts, a pair of levers are mounted in scissors fashion on the spring support with one end pivotally engaged with adjustment members. Positioned between the free ends of the levers is a bimetal element which actuates the levers in response to temperature variations to open and close the contacts. Movement of the adjustment members varies the temperature range at which the contacts will open and close.

For adapting the switch as either a high limit switch or a fixed temperature differential fan switch, an auxiliary spring is provided that can be selectively connected to the spring support to bias the contacts to return to either an open or close position upon removal of the external force applied by the bimetal. In either of these situations, it is necessary to use only one actuating lever and adjustment member.

Other objects and advantages of the invention will become apparent from the following description taken in connection with the accompanying drawings in which:

FIG. 1 is a top plan view of a fan switch with an adjustable temperature differential embodying the invention;

FIG. 2 is a sectional view taken on line 2—2 of FIG. 1;

FIG. 3 is a sectional view taken on line 3—3 of FIG. 2;

FIG. 4 is a view of the switch mechanism taken on

2

line 4—4 of FIG. 2 with the switch contacts illustrated in the open position;

FIG. 5 is a view similar to FIG. 4 with the contacts closed;

FIG. 6 is a sectional view taken on line 6—6 of FIG. 4;

FIG. 7 is an exploded perspective view of the switch mechanism with one wall of the switch casing broken away for clarity;

FIG. 8 is an exploded perspective view of the bimetal housing and base plate;

FIG. 9 is a top plan view of a fan switch with a fixed temperature differential embodying the invention;

FIG. 10 is a bottom view of the switch casing of FIG. 9;

FIG. 11 is a top plan view of an adjustable limit switch embodying the invention, and

FIG. 12 is a bottom view of the switch casing of FIG. 11.

FIGURES 1 through 8 illustrate the device arranged to function as a fan switch with an adjustable temperature differential, that is, the temperatures at which the switch contacts open and close can both be selected by adjusting the position of the actuating mechanism. In FIGURES 1

25 through 3, a switch casing 10 is mounted on a base plate 12 of a housing 14. Housing 14 is U-shaped in cross section having side members 16 and 18 and a top wall member 20. Mounted in housing 14 is a cantilevered bimetal element 22. One end of bimetal element 22 is

30 secured to the housing by rivets 23 with its free end extending toward base plate 12 and having an actuating tab 24 formed thereon. Housing 14 is positioned in an air duct of a heating system or the plenum of a furnace, and variations in temperature cause bimetal element 22 to deflect to provide actuating force for the switch mechanism. In order that the air or other temperature conducting medium may be distributed evenly about bimetal element 22, openings 26 are provided in the side and top walls of housing 14.

40 Secured to the inner side of the top wall of casing 10 (FIGURES 4 and 5) is a fixed electrical contact 28. Also secured to the top wall of the casing is a mainspring assembly 30. Mainspring assembly 30 includes a central portion 32 having a pair of resilient arm members 34 and 36 extending from its ends. Arm members 34 and 36 have their ends secured to the casing. Formed integrally with arm member 34 is a resilient contact lever 38 (FIG. 7) having a movable contact 40 secured adjacent its free end. Snap opening and closing of contacts 28 and 40 is provided by an overcenter spring 42 which has its end mounted between the end of contact lever 38 and the edge of central portion 32 of the mainspring assembly.

45 When central portion 32 of spring 30 is moved to the left as indicated in FIG. 5, overcenter spring 42 causes the end of contact lever 38 to deflect to the right until contact 40 closes against contact 28. Conversely, movement of central portion 32 to the right causes overcenter spring 42 to deflect contact 40 to the left to open the contacts, the position illustrated in FIG. 4. Spring assembly 30 is so designed that when deflected in either direction the biasing forces of arms 34 and 36 are balanced against the force of overcenter spring 42 so that the contacts will remain in either of the positions illustrated in FIGURES 4 and 5 unless central portion 32 is acted upon by an external force.

50 For transmitting the movement of bimetal element 22 to mainspring 30, a pair of actuating levers 44 and 46 of insulating material are pivotally mounted by rivet 48 to central portion 32 of spring 30. Actuating levers 44 and 46 are complementarily formed and, as illustrated, are mounted in scissors fashion on central portion 32.

Actuating levers 44 and 46 are provided with blades 50 and 52, respectively, in the form of pinchers which extend through a slot in base plate 12 and are disposed on opposite side of tab 24 of bimetal element 22. Projecting upwardly from levers 44 and 46 are handles 54 and 56, respectively, which extend through a slot in the upper wall of casing 10. Pivotal mounted on the top of casing 10 is a pair of adjustment arms 58 and 60 (FIG. 1) which are apertured at 62 and 64, respectively, and handles 54 and 56 are received in apertures 62 and 64. Adjustment arms 58 and 60 provide an abutment for levers 44 and 46 so that deflection of bimetal element 22 against one of the pincher ends of the levers will cause the lever to pivot about adjustment arm 58 or 60 and, acting through its pivotal connection 48 with central portion 32 of spring 30, will cause the spring assembly to shift either to the left or right to actuate the switch contacts.

By rotation of adjustment arms 58 and 60 about their pivots, the temperature range at which the switch contacts will be actuated may be varied. For example, counterclockwise rotation of adjustment arm 58 (FIG. 1) will cause blade 52 to move to the left as viewed in FIG. 3 and thus increase the amount of travel required by bimetal element 22 to actuate lever 44.

Adjustment arms 58 and 60 are complementary formed, and are pivotally mounted at their ends on a common axis at rivet 66. Apertures 62 and 64 are disposed over a slot 68 in the top wall of casing 10, slot 68 being elongated to permit movement of handle portions 54 and 56 upon adjustment of arms 58 and 60 about their pivotal axes at rivet 66. Adjustment arms 58 and 60 are of spring material and are biased to engage the top of the casing. Slotted holes 70 and 72 adjacent the ends of arms 58 and 60 respectively, cooperate with raised projections 74 formed on the top outer wall of the casing in an arcuate pattern to maintain the setting of the adjustment arms under vibration. Also provided adjacent the ends of the adjustment arms is a series of circular depressions 76 which are likewise arranged in an arcuate pattern for receiving pins (not shown) which can be used to provide either a maximum setting with a single pin, or a fixed setting by insertion of pins on opposite sides of each adjustment arm.

For indicating the temperature setting of the adjustment arms, a dial 78 with appropriate temperature markings is provided on the top wall for cooperation with the pointed ends of the adjustment levers 58 and 60. Dial 78 may be a gum-backed paper dial. Counterclockwise adjustment of adjustment arm 58 which is the "off" adjustment as indicated, reduces the temperature at which the switch contacts will open to shut down the fan. Clockwise pivotal adjustment of the "on" adjustment arm 60 toward the higher temperature setting of the dial increases the temperature at which the switch contacts will close to start the fan into operation.

With reference to FIGURE 7 the switch mechanism and its method of assembly is illustrated in detail. Switch casing 10 is of electrical insulating material and forms a substantially rectangular, open ended cavity having a front wall 80, side walls 82 and 84, rear wall 86 and a top wall 88. Side wall 82 is broken away in FIG. 7 to expose the interior of the casing. Projecting from top wall 88 adjacent side wall 84 is a post 90. Formed in side wall 84 is a vertical groove 92 having a projecting lip 94 for receiving arm member 36 of mainspring 30. Projecting from top wall 88 at substantially its longitudinal axis is an insulating rib 96 for electrically insulating the mounting plates of the fixed and movable contacts from each other. Holes 98 and 100 are formed in top wall 88 on either side of insulating rib 96 for receiving terminal screws and for mounting the contact plates on the casing.

Fixed contact 28 is mounted on an arm member 101

which is rigidly secured to a bracket 102 by a rivet 103. Bracket 102 is provided with a mounting plate 104 which is apertured at 106. Arm member 101 is fixed against rotation by the cooperation of a tab 107 with a notch 107a. Bracket 102 is secured to the casing by a terminal nut 108 (FIG. 2) which is received in hole 110 and aperture 106, with its inner end spun over at 110 to clamp plate 104 to the casing. For preventing rotation of bracket 102 about nut 110, a lip 112 at the forward end of bracket 102 cooperates with a slot 114 in top wall 88 of the casing.

Arm member 36 of mainspring 30 is offset at 116, and an auxiliary spring arm 118 extends from the end of arm member 36 for a purpose to be described below. Arm member 34 is secured to a bracket 120 having a mounting plate 122. Cooperating holes 124 and 125 in bracket 120 and arm member 34, respectively, receive rivets 126 to secure the parts together. Bracket 120 is secured to the casing with a terminal nut 128 (FIG. 1) in the same manner as bracket 102 and extends along the length of contact lever 38 to serve as a stop plate for contact 40 (FIGS. 4 and 5). Slots 42a in over-center spring 42 receive tabs 32a and 38a formed on central portion 32 and contact lever 38, respectively.

Mounting lugs 130 and 132 having holes 131 and 133, respectively formed therein, are integrally formed on the outside of front wall 80 of the casing for receiving fasteners to secure the casing to base plate 12. Formed on the outside of rear wall 86 is a boss 134 having a slot 135 and a groove 136 formed therein. Groove 136 cooperates with a similar groove on base plate 12 for receiving a mounting bolt. Integrally formed on the top wall of casing 10 is a pair of stops 138 for limiting the outward movement of adjustment arms 58 and 60. Walls 140 project upwardly from the top wall of the casing to form a pair of cavities, substantially rectangular in shape for receiving terminal screws 142 and 144 in nuts 108 and 128, respectively. Rivet 66 for mounting adjustment arms 58 and 60 on casing 10 is received in a mounting hole 146 in the top wall of the casing.

Main spring 30 is firmly secured adjacent top wall 88 by insertion of the end of arm member 36 into groove 92. Offset portion 116 of arm member 36 cooperates with post 90 to provide a force fit between lip 94 of groove 92 and post 90. As pointed out previously, when main spring 30 is in the position illustrated in FIG. 4 with contacts 28 and 40 open, an external force to the left on central portion 32 is required in order to close the contacts due to the action of over center spring 42. After contacts 28 and 40 are closed as illustrated in FIG. 5, an external force to the right on central portion 32 is required in order to open the contacts. Rib 96 serves to electrically insulate plate 104 from lug 122 of bracket 120.

Referring to FIG. 8, base plate 12 is provided with three depressions 146, each having a slot 147 for receiving tabs 148 of bimetal housing 14 which are bent over after insertion into slots 147 (FIGS. 2 and 3). Blades 50 and 52 of the actuating levers extend through an elongated slot 150 formed in base plate 12 which is covered by an air stop 152 of nylon or some other flexible material. Air stop 152 is provided with a slit for receiving the blade. For cooperation with slot 135 in boss 134 of the switch casing, a tab 154 is bent upwardly on base plate 12 for insertion into the slot. Apertured recesses 156 and 158 are formed at the forward end of base plate 12 for cooperation with openings 131 and 133 to receive screws 160 (FIG. 1) which secure casing 10 to base plate 12. Mounting grooves 162 and 164 are formed at the front and rear edges of base plate 12 for mounting the assembly on the wall of a duct or other support. After assembly of main spring 30 and switch contacts 28 and 40 in casing 10, the casing is secured to base plate 12 by inserting tab 154 into slot 135, after which tab 154 is then bent over to hold the switch in place as shown in FIG. 1. Screws 160

engage the threaded holes in recesses 156 and 158 to complete the assembly. Before tightening screws 160, however, slight rotation of the switch on tab 154 is possible, permitting limited calibration of the switch relative to the position of bimetal 22 in housing 14. Adjustment arms 58 and 60 are then pivotally fastened to casing 10 by rivet 66. The structure described thus far operated as fan control with an adjustable temperature differential.

After assembly and temperature calibration, bimetal housing 14 is inserted into an appropriate opening in a duct or plenum of a forced air furnace, and base plate 12 is mounted to the duct by fasteners which cooperate with slots 162 and 164. Electrical connection with the fan motor is accomplished by connecting wires from the fan motor in series with the switch by terminal screws 140 and 142.

The electrical circuit through the switch can best be described with reference to FIGS. 4 and 5. Current flows from terminal 140 through bracket 120 to main spring 30 which carries contact 40. Ribs 96 insulate contact 40 from contact 28 when the switch is open as illustrated in FIG. 4.

Referring to FIG. 3, upon an increase in temperature bimetal 22 deflects to the left to actuate lever 44 and shift central portion 32 of spring 30 to the left as viewed in FIG. 5, causing over-center spring 42 to close the contacts with a snap action, and the current flows from contact 40 to contact 28 and through bracket 102 to terminal 142. Upon satisfaction of the heating requirement and resultant cooling of bimetal 22, bimetal 22 deflects to the right as viewed in FIG. 3 and acts on blade 50 of actuating lever 46 to shift central portion 32 of spring 30 back to the position illustrated in FIG. 4 to snap open the contacts, thereby shutting off the fan.

Movement of the "on" adjustment arm 60 to a higher temperature setting, that is, counterclockwise as viewed in FIG. 1 moves blade 50 of actuating lever 44 to the right as viewed in FIG. 3 requiring a greater amount of deflection of bimetal 22 to contact the pincher end of blade 50 which results in a higher fan "on" temperature setting. Conversely movement of the adjustment arm 60 to a lower temperature setting results in the switch contact being closed with less deflection of bimetal 22 providing a lower fan "on" setting.

When adjustment arms 58 and 60 are positioned adjacent to each other as illustrated in FIG. 1, bimetal 22 is confined between the pincher end of blades 50 and 52 with no free travel, providing a minimum temperature differential of approximately 25 degrees Fahrenheit as presently designed. Separation of the "off" adjustment arm 58 from the "on" adjustment 60 results in separation of blades 50 and 52 with a corresponding free movement of actuating tab 24 of bimetal element 22 between the spaced blade ends before contact is made in either direction, to throw the switch to "on" or "off" position. This free movement results in the attaining of an increased fan switch differential depending upon the degree of separation of blades 50 and 52.

For adapting the device to function as a fan switch with a fixed temperature differential, adjustment arm 58 and 60 actuating lever 46 are omitted as illustrated in FIGS. 9 and 10. Auxiliary spring 118 is utilized to provide the actuating force for mainspring 30 in opposition to force induced by deflection of bimetal element 22. With reference again to FIG. 7, a slot 166 is provided in central portion 32 of mainspring 30 adjacent arm member 36. Auxiliary spring 118 is provided with three leaves, 118a, 118b and 118c. Any or all of leaves 118a, 118b or 118c can be inserted into slot 166 as illustrated in FIG. 10, to exert a biasing force to the right on central portion 32 tending to separate contacts 28 and 40, providing a normally opened switch. Upon heating of the bimetal element 22, central portion 32 is deflected to the left as viewed in FIG. 10 against the bias of auxiliary spring 118, until overcenter spring 42 causes the contacts to snap

closed. As bimetal element 22 deflects in the opposite direction upon cooling, auxiliary spring 118 causes central portion 32 of spring 30 to follow the movement of the bimetal to the right until contacts are opened with a snap action as illustrated in FIG. 10, thereby providing a fixed minimum fan differential.

FIGS. 11 and 12 illustrate the device as utilized as an adjustable limit switch with the "on" adjustment arm 60 and actuating lever 44 omitted. Auxiliary spring 118 is bent to the configuration illustrated in FIG. 12 to exert a biasing force to the left on central portion 32 providing a normally closed switch.

When used as a limit switch as shown in FIGS. 11 and 12, bimetal element 22 is reversed in housing 14 so that upon heating it will deflect in a direction to cause main spring 30 to move to the right, resulting in opening contacts 28 and 40 as the pre-set "limit off" temperature is reached. Dial 78 is provided with temperature markings in reversed order from that of dial 78 in FIGS. 1 and 9, to correspond to the reverse action of bimetal 22.

As previously pointed out, all of the adjustable switches can be converted to maximum setting switches by insertion of stop pins in apertures 76 on the switch casing, or if a fixed setting is desired, adjustment arm 58 and/or 60 can be confined to a desired fixed setting by locating stop pins on opposite sides of the adjustment arm in apertures 76 after properly positioning the adjustment arms to the desired setting.

While specific examples of the invention have been illustrated and described, it will be understood that the invention is not confined to the exact construction illustrated, but that the various alterations in construction are possible within the scope of the invention as defined by the appended claims.

What is claimed is:

1. A thermally responsive switch comprising, a switch casing, a mainspring mounted in the casing, a movable contact carried by the mainspring, a fixed contact in the casing, a pair of levers pivotally mounted in scissors fashion on the mainspring, adjustment means on the casing,

each of the levers having one end rotatably engaged with the adjustment means, and a thermally responsive movable element connected with the casing,

the free ends of the levers being positioned in the path of movement of the thermally responsive element for moving the movable contact into and out of engagement with the fixed contact in response to temperature changes.

2. A thermally responsive switch comprising, a switch casing,

a mainspring mounted on one wall of the casing, a resilient arm member on the mainspring, a movable contact carried by the resilient arm member, an overcenter spring connected with the arm member and the mainspring for causing movement of the movable contact in one direction with a snap action upon movement of the mainspring in the opposite direction,

a fixed contact in the casing, a pair of levers mounted in scissors fashion on the mainspring, adjustable stop means on the casing,

one end of each of the levers engaged with the stop means for pivotal movement relative to the stop means, an actuating element connected with the casing and movable in response to temperature changes,

and the free ends of said levers being disposed on opposite sides of the actuating element in the path of movement thereof for opening and closing said contacts in response to temperature variations.

3. A thermally responsive switch comprising,
a switch casing,
a mainspring including,
    a central portion,
    an arm member extending from each end of the central portion,
    each arm member having its end fixedly mounted on the casing,
    a resilient contact arm formed on one of the arm members and having a free end extending toward the central portion,
    a movable contact mounted on the free end of the contact arm,
    a fixed contact mounted in the casing,
    an overcenter spring mounted between the free end of the contact arm and the central portion operative to open and close the contacts with a snap action upon movement of the central portion,
    and an actuating element connected with the central portion for moving the central portion in response to temperature variations to actuate the contacts. 15
4. A thermally responsive switch as defined in claim 3 further including,
abutment means on the casing,
a pair of oppositely formed levers mounted in scissors fashion on the central portion of the mainspring, 25
    each of the levers having one end rotatably engaged with the abutment means,
    the levers having free ends disposed on opposite sides of the actuating element in the path of movement thereof,
said actuating means operative for moving the free end of one of the levers in a direction to close the contacts upon a decrease in temperature, and operative for moving the free end of the other of the levers in a direction to open the contacts upon an increase in temperature. 35
5. A thermally responsive switch as defined in claim 4 further including,
means for adjusting the position of said abutment means for varying the temperature response of said levers. 40
6. A thermally responsive switch as defined in claim 3 further including,
an auxiliary spring arm formed on the other of the arm members of the mainspring,
the auxiliary spring arm having a free end selectively engageable with the central portion of the mainspring to resiliently bias the contacts either open or closed,
and said actuating element being operatively connected to move the central portion against the bias of the auxiliary spring in response to temperature variations. 50
7. A thermally responsive switch as defined in claim 3 further including,
abutment means on the casing,
a lever pivotally mounted intermediate its end on the central portion of the mainspring,
said lever having one end rotatably engaged with the abutment means and its other end disposed in the path of movement of the actuating element,
an auxiliary spring selectively engageable with the central portion of the mainspring to bias the contacts closed,
and said actuating element being operative to engage the free end of the lever and move the central portion in a direction to open the contacts in response to an increase in temperature. 65
8. A thermally responsive switch comprising,
a casing having side walls and a top wall,
a slot in the top wall,
a pair of adjustment arms pivotally mounted on the top wall,
each of the adjustment arms having an aperture radially displaced from the pivotal axis of the arms for co- 70

- operating with the slot upon pivotal movement of the arms,
a mainspring having a central portion and a pair of arm members extending from the central portion,
    said arm members having their ends mounted on the opposite side of the top wall from the adjustment levers,
a movable contact carried by one of said arm members, a fixed contact mounted in the casing in the path of movement of the movable contact,
a pair of oppositely formed actuating levers pivotally mounted in scissors fashion on the central portion of the mainspring,
each of the actuating levers having one end received in an aperture of one of the adjustment arms,
the actuating levers having free ends disposed in opposed relationship on the opposite side of the central portion from said one end,
an actuating element having a portion movable in response to variations in temperature,
    said movable portion being disposed between the free ends of the levers for actuating one of the levers in response to a preset low temperature to close the contacts, and actuating the other of the levers in response to a preset high temperature to open the contacts,
said adjustment arms being selectively positionable about their pivotal axes to vary the range between the high and low temperatures.
9. A thermally responsive switch comprising,
a casing having side walls and a top wall,
a pair of adjustment arms pivotally mounted on the top wall,
each of the adjustment arms having an aperture formed therein spaced from its pivotal axis,
a fixed contact and a movable contact in the casing, movable support means for the movable contact,
a pair of actuating levers pivotally mounted in scissors fashion intermediate their ends on the movable support means,
each of the actuating levers having one end received in the aperture of one of the adjustment arms and a free end disposed in opposed relationship to the free end of the other actuating lever,
and a thermally responsive actuating element disposed between the free ends of the actuating levers and operative in response to decreases in temperature to pivotally actuate one of the actuating levers about said aperture to close the contacts, and operative in response to increases in temperature to pivotally rotate the other of the actuating levers about the apertured adjustment arm to open the contacts. 50
10. A thermally responsive switch as defined in claim 9 including,
a plurality of raised projections arranged in an arcuate pattern on the top wall of the casing in the path of movement of the adjustment arms,
said adjustment arms being resiliently biased toward the top wall and selectively engageable with the projections for restraining the adjustment arms against rotation.
11. A snap acting switch comprising,
a casing,
a main spring in the casing including,
    a central portion,
    a pair of resilient arm members integrally formed with the central portion,
        one of the arm members extending from one end of the central portion with its end secured to the casing,
        the other of the arm members extending from the other end of the central portion with its end secured to the casing,
    a fixed contact in the casing,
    a resilient contact lever formed integrally on said one

arm member having a free end extending toward the control portion,
a movable contact carried by said contact lever movable into and out of engagement with the fixed contact,
an overcenter spring mounted between said one end of the central portion and the free end of the contact lever,
and means for moving the central portion laterally with respect to the ends of the arm members in response to temperature changes to open and close the contacts with a snap action.

10
12. A thermally responsive switch as defined in claim 11 including,

an offset portion on the other of the arm members, 15
an auxiliary spring arm integrally formed on the offset portion extending substantially parallel to said other arm member toward the central portion,
a slot in the central portion adjacent said other end thereof,
the free end of the auxiliary spring arm being selectively

5

20

engageable with the slot to bias the central portion in a direction to open the contacts.

13. A thermally responsive switch as defined in claim 11 including,

an offset portion on the other of the arm members, an auxiliary spring arm integrally formed on the offset portion extending substantially parallel to the other arm member toward the central portion, the free end of the auxiliary spring arm being selectively engageable with the central portion to bias the central portion in a direction to close the contacts.
